UNITED STATES PATENT OFFICE.

EMMONS WOODBURY SAWYER, OF MINNEAPOLIS, MINNESOTA.

CARD GAME.

1,228,607.

Specification of Letters Patent. Patented June 5, 1917.

Application filed March 6, 1917. Serial No. 152,621.

To all whom it may concern:

Be it known that I, EMMONS WOODBURY SAWYER, a citizen of the United States of America, residing at 1506 Emerson avenue, north, Minneapolis, in the county of Hennepin and State of Minnesota, have invented certain new and useful Improvements in Card Games, of which the following is a specification.

10 My invention relates to card games, and has for its object to provide a set of cards having thereon certain markings and sets of markings whereby many original, unique, and interesting combinations can be made, 15 upon which combinations a very large number of pleasing games of skill and chance may be founded.

More specifically, the game consists of four groups of thirteen cards each, each 20 group being distinguished by a different color and each group having the cards thereof consecutively numbered one to thirteen; each of said cards also has thereon a letter of the alphabet. These letters are not duplicated on any one group. Each group has one complete set of vowels. Certain other 25 letters are found in each of two groups; and certain letters appear only in one group. Each of the groups has some letters not 30 found in any other group.

The full objects and advantages of my invention will appear in connection with the detailed description thereof, and are particularly pointed out in the claims.

35 In the drawings illustrating the application of my invention in one form,—

Figure 1 illustrates one group of cards having a distinguishing color, such as red. Fig. 2 illustrates a second group of cards 40 having a distinguishing color, such as black. Fig. 3 illustrates a third group of cards with a third color, such as green; and Fig. 4 illustrates the fourth group of cards having a fourth color, such as blue.

45 All of the cards will preferably have white faces with the lines, letters, and numbers printed in the respective colors, the backs of the cards being of any desired design.

Each of the groups of cards, as shown, is 50 consecutively numbered 1, 2, 3, 4, 5, 6, 7, 8, 9, 10, 11, 12, 13, the numbers appearing in the upper left hand and the lower right hand corner of each card and appearing in reversed position within rectangles 10 and 55 11, as indicated at 12 and 13. In whichever position the cards are held, therefore, a num-

ber and a letter will appear in the upper left hand corner and the lower right hand corner, and similarly a number and a letter will appear in proper upright position in 60 the rectangle at the top of the card. Each of the groups has one each of vowels A, E, I, O, U; but these vowels in the different groups do not appear in conjunction with the same number; thus A is on card 12 of 65 group one, on card 7 of group two, on card 2 of group three, and on card 9 of group four; E is on card 1 of group one, card 12 of group two, card 4 of group three, and card 8 of group four; I is on card 9 of 70 group one, card 5 of group two, card 13 of group three, and card 2 of group four; O is on card 8 of group one, card 9 of group two, card 3 of group three, and card 12 of group 4; U is on card 3 of group one, card 75 4 of group two, card 8 of group three, and card 11 of group four. The exact distribution of these vowels need not be precisely as here shown; but it is a principle of the invention that the vowel letters of each 80 group are on different numbered cards from the corresponding vowel letters of any other group. In the case of the following consonants B, C, D, F, L, M, N, P, R, S, and T, each appears in two groups of cards so 85 that there are two of each of said consonants in the entire set of cards, distributed irregularly through the four groups. Thus, in the arrangement shown, there are seven of such consonants in group one, four of such consonants in group two, six of such consonants in group three, and five of such consonants in group four. None of these consonants last referred to, are found twice in any one 90 group of cards. The following consonants G, H, J, K, Q, V, W, X, Y, Z appear only once and consequently each is found in only one group of cards. Thus in the arrangement shown, of these consonants Z appears 95 in group one; G, J, Q, Y, appear in group two; V, X appear in group three and H, J, W appear in group four.

As above stated, the exact arrangement of these letters shown is not essential but the arrangement is such that the same number of consonants of any class is not found in any of the four groups of cards.

In general, the play is instituted by dealing in the usual manner, either all or a requisite number of cards of the pack. Two, three, or four players most commonly comprise the number most suitable for any of

the games which may be played with these cards. In general, 13 is the high card and 1 the low card; and trump is determined by color. An essential feature of my game, 5 however, is that the scoring card or the trick taking cards may be determined by the letter or by the matching of letters. Also sequences of letters found in one hand or which may be procured by exchanging 10 or other methods of play form important counting combinations in many games.

A large number of different games is made possible by the peculiar arrangement of letters in combination with the consecutive numbering of the different groups. In one game, ten cards are dealt to each player. The card played by the first player must be followed in suit or color by the other players, but if a player is out of suit and 20 can match a letter already played, the player so matching wins over any other suit card. If two players match, as where three or more of the same vowels appear on the board at once, the last to match wins the 25 trick. The peculiar grouping of letters in the several sets of cards, four each of the vowels, two each of some of the consonants, and only one of other consonants, gives a fair hazzard of letter matching, and at the 30 same time renders it of such doubtful occurrence as to greatly heighten the interest found therein.

In another form of game, nine cards are dealt to each player. Thereafter, beginning with the leader, each player in turn draws a card from the remainder of the pack, the purpose being to make combinations in sequences of letters of the alphabet as ABC, BCD, etc. or to match letters 35 of the alphabet as AAA, or to obtain vowel groups of three, as AEI. These combinations count for the player the total of the numbers found on its three cards. Because 40 of the peculiar arrangement of letters in which there are certain letters of one each only in the pack, others of two each in the pack, and still others of four each, and the 45 irregular distribution of these letters in respect to the numerals, the combinations are 50 rendered difficult to secure and the results of such combinations in respect to the counting sums of the numbers thereon are made interestingly uncertain.

A further description of the multiplicity of uses of the cards having the arrangements 55 herein described is unnecessary. The advantages of my invention are obvious, as by these means games of much variety and interest may be played while avoiding the unpleasant association which to some render 60 the use of what are known as common playing cards obnoxious.

I claim:

1. A deck of cards comprising four groups of equal number, the cards of each group being marked to distinguish the same from the cards of each other group, the cards of each group being consecutively numbered, and each card of each group having a different letter of the alphabet thereon, some of said letters appearing on a card of each group, others of said letters appearing on a card of each of two groups and still others of said letters appearing on a card of only one group.

2. A deck of cards comprising four groups of equal number, the cards of each group being marked to distinguish the same from the cards of each other group, the cards of each group being consecutively numbered, and each card of each group having a different letter of the alphabet thereon, each group having the cards thereof marked with one each of the vowels A, E, I, O, U, each of said vowels appearing 75 on a different numbered card on each group.

3. A deck of cards comprising four groups of equal number, the cards of each group being marked to distinguish the same from the cards of each other group, the cards of each group being consecutively numbered, and each card of each group having a different letter of the alphabet thereon, each group having the cards thereof marked with one each of the vowels A, E, I, O, U, each 80 of said vowels appearing on a different numbered card on each group, a portion of the consonants appearing on a card of each of two groups and the remaining consonants appearing on a card of only one group.

In testimony whereof I have affixed my signature in presence of two witnesses.

EMMONS WOODBURY SAWYER.
